UNITED STATES PATENT OFFICE.

MAX KLEIN, OF NEW YORK, N. Y.

DESIGN FOR A WALL BRACKET FOR LIGHTING FIXTURES.

Application filed November 17, 1923. Serial No. 7,791. Term of patent 7 years.

To all whom it may concern:

Be it known that I, MAX KLEIN, a citizen of the United States, residing at New York, in the county of New York and State of New York, have invented a new, original, and ornamental Design for a Wall Bracket for Lighting Fixtures, of which the following is a specification, reference being had to the accompanying drawing, forming part thereof.

The figure is a front view of a wall bracket for lighting fixtures showing my design.

I claim:

The ornamental design for a wall bracket for lighting fixtures, as shown.

MAX KLEIN.
